G. KEITH.
GAS BURNER.
APPLICATION FILED SEPT. 19, 1916.

UNITED STATES PATENT OFFICE.

GEORGE KEITH, OF LONDON, ENGLAND, ASSIGNOR OF ONE-HALF TO JAMES KEITH, OF LONDON, ENGLAND.

GAS-BURNER.

1,210,654.

Specification of Letters Patent. Patented Jan. 2, 1917.

Application filed September 19, 1916. Serial No. 121,029.

To all whom it may concern:

Be it known that I, GEORGE KEITH, a subject of the King of the United Kingdom of Great Britain and Ireland, and residing at London, England, have invented a certain new and useful Improvement in Gas-Burners, of which the following is a specification.

This invention relates to improvements in gas burners, and more particularly to burners of the type provided with an outlet extending longitudinally of the burner tube.

In practice it is found that a burner of the type referred to tends to burn more gas at the end adjacent to the injector than at the end remote therefrom, there being a gradual diminution of the volume of gas consumed along the length of the burner proceeding from the end adjacent to the injector, whereas generally with similar long burners used for heating with different forms of outlet the tendency is for the consumption to increase toward the end remote from the injector.

Particularly in connection with the adaptation of such burners to biscuit ovens and the like where the burners are disposed transversely of the chain on which the biscuit pans move, it is desirable that there should be provision for controlling the delivery of the combustible mixture at different points along the length of the burner; indeed, this would be the case even were the burners designed to deliver the combustible mixture uniformly, as cooling influences may affect different parts of the oven differently and, on account of changes in conditions, it is important that an attendant on the spot should be able to effect the necessary adjustment. Practically adequate results may be obtained by increasing temporarily the heating effect of one end of the burner at the expense of the other, as may be effected by the preferred arrangements hereinafter described.

Broadly regarded, the invention consists in a gas burner comprising a tube provided with a longitudinal apertured partition or diaphragm dividing the tube into separate chambers, one such chamber being formed with an outlet in the form of a continuous slot extending longitudinally of the tube and the other chamber communicating with the first by way of the apertures in the par-

tition, and a valve device fitted to the tube adjacent to the inlet end and adjustable to control the distribution of the inflowing mixture so as to confine the mixture to enter the second compartment or in part to 60 by-pass such compartment.

In the accompanying drawings, Figure 1 is a longitudinal section showing one construction of burner embodying the invention; Figs. 2 and 3 are transverse sections 65 on the lines A—A and B—B respectively (Fig. 1), Fig. 2 showing the by-pass valve, which in the instance illustrated is longitudinally adjustable, and Fig. 3 showing the partition as of D-form in section. Fig. 4 is 70 a part elevation part longitudinal section showing a burner of modified construction provided with a circularly adjustable valve and fitted with a partition of modified form. Figs. 5 and 6 are transverse sections on 75 the lines C—C and D—D respectively (Fig. 4) illustrating the construction modified as above stated.

On reference to the drawings it will be seen that the burner tube 1 is divided longitudinally into two chambers 2—3 by the tubular or split tubular diaphragm or partition 4 the upper wall of which bears against the transverse screws 5, the interior of the tubular diaphragm constituting the chamber 85 86 3.

In order to reduce leakage from one chamber to the other the diaphragm may be of D-shape, as shown in Fig. 1, or substantially D-shape, as shown in Fig. 4, including a plane wall and a wall curved in substantial conformity with the curvature of the tube.

From the end of the tubular diaphragm adjacent to the injector (not shown) a connection is taken to the latter, so that normally the whole of the mixture passes into the chamber 3.

The diaphragm 4 is apertured at intervals at 6, the apertures being preferably 100 formed for example as shown in Fig. 1 as narrow longitudinal slots the distribution of which may be experimentally determined; preferably the slots are distributed so that normally the delivery of the mixture 105 through the same is greatest at the end of the burner remote from the injector.

To provide for adjustment of the distribution, there is employed a valve device for by-passing the chamber 3 and admitting 110

the bulk of the mixture into the chamber 2, that is into the upper half of the burner tube, the arrangement being such that when the by-pass is full open the maximum delivery is at the end of the burner adjacent to the injector.

According to the adjustment of the valve device distribution intermediate the two extremes is obtainable. For example, as shown in Figs. 1 and 2 the valve device employed may comprise a short D-shaped tube 7 which fits snugly into the end of the tubular diaphragm 4, adjacent to the injector, and the plane portion of which is adapted to cover an aperture 8 of suitable area in the plane portion of the diaphragm, thus forming a sliding damper. To provide for convenient displacement of the damper, there may be fixed to the plane portion of the latter a stud 9 one end of which projects through the by-pass aperture 8 and the other end of which projects into the interior of the tubular diaphragm 4, such stud being engageable by a rod pushed through the throat of the injector and capable of being conveniently manipulated by the attendant. By reason of its formation, the damper is sufficiently resilient to lock itself in any position into which it is shifted.

In the construction of burner shown in Figs. 4 to 6, the diaphragm 4^a is of deformed circular shape and is formed with lateral apertures 6^a, the object of the lateral disposition of the apertures being to avoid local enlargement of the flame. The apertures 6^a may be suitably spaced or grouped as may be determined by experiment so as to effect the desired distribution.

At the end adjacent to the injector the inner wall of the diaphragm 4^a constitutes a surface of revolution, being in the instance shown of cylindrical form, and serves to sleeve a tubular valve 10 circularly adjustable to bring a port or ports therein into or out of communication with a port or ports in the wall of the diaphragm.

It will be seen that the arrangement is such that the volume of mixture by-passing the chamber 3 enters the chamber 2 at the lower side of the burner tube, tendency to local increase of the flame issuing at the outlet being thus reduced.

What I claim is:—

1. A gas burner comprising, in combination, a tube having an outlet in the form of a

continuous slot extending longitudinally thereof and means for controlling the delivery at different points along the length of the tube while maintaining a constant effective area of the outlet.

60

2. A gas burner comprising, in combination, a tube partitioned longitudinally into separate chambers, one such chamber being formed with an outlet in the form of a continuous slot extending longitudinally of the tube and the other chamber communicating with the first by way of apertures in the partition, and a valve device fitted to the tube adjacent to the inlet end and adjustable to control the distribution of the inflowing mixture so as to confine the mixture to enter the second chamber or to cause the same in part to by-pass such chamber in its passage to said first named chamber.

70

3. A gas burner comprising, in combination, a tube having an outlet in the form of a continuous slot extending longitudinally thereof, an apertured tubular partition fitted in said tube and means adjustable to direct the whole or a part only of the inflowing mixture into the interior of said tubular partition.

75

4. A gas burner comprising, in combination, a tube having an outlet in the form of a continuous slot extending longitudinally thereof, an apertured tubular partition of substantially D-shape fitted in said tube, screws disposed transversely of said tube and bearing on the plane face of said D-shaped partition, and means for directing inflowing mixture wholly or in part into the interior of said tubular partition.

80

5. A gas burner comprising a tube divided longitudinally into two chambers intercommunicating through a longitudinal series of apertures, one of said chambers having an outlet in the form of a longitudinal slot, and the other of said chambers having a gas inlet at one end thereof, and means adjacent to said inlet and adjustable to direct all of the gas entering said inlet into said last-named chamber or to divert a portion thereof into said first-named chamber.

85

In testimony whereof I have signed my name to this specification in the presence of two subscribing witnesses.
